UNITED STATES PATENT OFFICE.

RALPH L. MORGAN, OF WORCESTER, MASSACHUSETTS.

WIRE-DRAWING MACHINE.

975,979.

Specification of Letters Patent. Patented Nov. 15, 1910.

Application filed March 5, 1906. Serial No. 304,182.

To all whom it may concern:

Be it known that I, RALPH L. MORGAN, a citizen of the United States, residing at Worcester, in the county of Worcester and 5 Commonwealth of Massachusetts, have invented a new and useful Improvement in Wire-Drawing Machines, of which the following is a specification, accompanied by drawings forming a part of the same, in 10 which—

Figure 1 is a plan view of a wire drawing machine embodying my invention, and Fig. 2 is a central sectional view of a wire drawing capstan.

15 Similar reference letters and figures refer to similar parts in the different views.

My invention relates to improvements in capstans for continuous wire drawing machines, whereby I prevent the removal of 20 small particles of metal from the wire seat by the friction of the wire, and the consequent clogging of the dies by such particles, and it consists in the construction and arrangement of parts as hereinafter described 25 and pointed out in the annexed claim.

Referring to the accompanying drawings 1 denotes the frame of the wire drawing machine. The pulley 2, journaled in the frame 1, is driven by suitable connection with the 30 source of power, not shown, and the pulley 2 by means of the gears 3, 4 and 5 drives the shafts 6 and 7. The wire 8 is drawn through the dies *a*, *b* and *c* in the die box 9 by the capstan 10 on the shaft 6. After each operation of drawing it passes beneath the die box around the scored idlers 11, 12 and 13 respectively, which change its direction and it is finally drawn through the die *d* in the die box 9 by the drum 14 turning with the 35 shaft 7.

The capstan 10, as shown in Fig. 2, is composed of disks 15, having between them annular wire seats 16. The wire seats 16 are

composed of wood or other nonmetallic substance having elongated and flexible fibers of 45 a character different from the granular particles of the wire, and are firmly held between the disks 15 by the nut 17 which draws the disks 15 together and against the shoulder 18 on the shaft 6. By thus making the 50 wire seats 16 of a nonmetallic material I prevent the attrition of metal on metal as the wire passes over the wire seats, and the consequent erosion of minute particles of metal from the wire seats, which are liable 55 to be carried by the wire into the dies and tend to clog or obstruct the free passage of the wire through the dies. By making the wire seats of nonmetallic material of the character above described, however, the particles worn from them by the passage of the wire are fibrous or elongated in character and have a tendency to be removed from the wire when it enters the die. By thus varying the character and shape of the particles 60 worn from the wire seats the dies are 65 enabled to keep themselves clear and free of any foreign substance that would tend to retard the passage of the wire.

I claim,

A continuous wire drawing machine having a series of dies, a rotating capstan provided with wire drawing seats in contact with which the wire is drawn through the dies and from which the wire passes to the 75 succeeding dies, said wire forwarding seats composed of a material having elongated and flexible fibers so that the fibers worn from each seat by the wire in its passage will be such as to be engaged by the mouth 80 of the succeeding die, and means for rotating said capstan.

RALPH L. MORGAN.
